BOBBIN STRIPPER

William Lonzo, Fitchburg, Mass., assignor to
Charles H. Whitcomb, Fitchburg, Mass.

Application August 17, 1933, Serial No. 685,597

9 Claims. (CL. 28—19)

This invention relates to a machine for removing the weft ends from bobbins ejected from a weft replenishing automatic loom. It is customary in the operation of such looms to provide weft detecting mechanism which will initiate weft replenishment and eject a substantially exhausted bobbin just before the weft runs entirely off on the bobbin. The remaining weft end extending to the ejected bobbin is then severed by special thread-cutting devices and a few turns of weft are commonly left on each ejected bobbin. The removal of these weft ends is a rather troublesome matter, particularly in connection with silk looms where no abrasion or other injury of the surface of the bobbin is permissible.

It is the general object of my invention to provide improved pneumatic means for removing the weft ends from the ejected bobbins, without injury to the bobbin surface and without contact of any mechanical structure therewith.

A further object of the invention is to provide a continuously operating machine in which the only duty of the operator is to place the ejected bobbins in position on a continuously moving conveyor belt.

My invention further relates to arrangements and combinations of parts which will be hereinafter described and more particularly pointed out in the appended claims.

A preferred form of the invention is shown in the drawings, in which

Fig. 1 is a front elevation of my improved bobbin stripper;

Fig. 2 is an end view, looking in the direction of the arrow 2 in Fig. 1;

Fig. 3 is a detail sectional view of a portion of the conveyor, taken along the line 3—3 in Fig. 2;

Fig. 4 is a detail elevation, looking in the direction of the arrow 4 in Fig. 1;

Fig. 5 is an enlarged partial front elevation of the stripper roll;

Fig. 6 is an enlarged plan view of certain parts, looking in the direction of the arrow 6 in Fig. 1;

Fig. 7 is a sectional elevation, taken along the line 7—7 in Fig. 6, and

Fig. 8 is a detail end elevation, looking in the direction of the arrow 8 in Fig. 1.

Referring to the drawings, my improved bobbin stripper comprises a frame 10 having a table portion 11 (Fig. 7). A conveyor belt 14 is

mounted on a driving pulley 15 at one end and on a guide pulley 16 at the other end.

The guide pulley 15 is mounted on a cross shaft 20 (Fig. 2) rotatable in bearings 21 on the frame 10 and provided with a large pulley 22 at the rear end of said shaft. The pulley 22 is connected by a belt 23 to a small pulley 24 on a cross shaft 25 mounted in bearings 26 carried by an upper or auxiliary frame 30.

A large pulley 32 (Fig. 2) is secured on the shaft 25 and is connected by a belt 33 to a small pulley 34 on the armature shaft of a driving motor M. The shaft 25 is thus rotated at reduced speed relative to the speed of the motor and the shaft 20 is rotated at a still further reduced speed.

The conveyor pulleys 15 and 16 are so located that the upper run of the conveyor belt 14 is above the table portion 11 of the main frame 10, while the lower run of the belt 14 is below said portion 11.

A supporting member or runway 40 is provided above the table 11 to support the belt during its horizontal upper or operative run, and guide members 41 (Fig. 7) are provided to prevent lateral displacement of the belt. Similarly, guide members 43 are supported below the table 11 and side strips 44 are mounted on the members 43 and constitute a runway to support the belt during its return travel.

Spaced blocks 50, preferably of wood, are secured to the outer surface of the conveyor belt 14, and pins 52 extend outward from the blocks 50 in which they are firmly secured. On the return run, the blocks 50 engage the side strips 44 and thereby support the belt 14.

A stripper roll 60 provided with a roll shaft 61 is mounted in a swivel bearing 62 (Fig. 1) at the driving end and in a bearing bracket 63 at the other end. The bracket 63 is detachably secured on the frame member 64 by a clamping screw 65. The roll 60 is tapered from the driving end and is provided with a removable cloth casing 66, preferably having a roughened surface to which threads will readily adhere.

A small friction roll 68 is axially adjustable on the extended driving end portion of the roll shaft 61 and is positioned to engage the face of a friction disc 69 secured to the large pulley 32 on the cross shaft 25. The stripper roll 60 is thus continuously rotated and the speed may be varied by adjusting the small friction pulley 68 along the roll shaft 61 to vary the driving radius of the disc 69.

A main air supply pipe 70 (Fig. 4) is con-

nected through a valve 71 to branch pipes 72 and 73, which in turn are connected to front and rear perforated tubes 74 and 75, which tubes extend longitudinally of the machine and adjacent the upper run of the conveyor belt 14 at the front and rear thereof.

The perforations 76 in the tubes 74 and 75 are angularly disposed, as indicated in Fig. 7, and deliver jets of air under pressure in an upwardly inclined direction against the lower parts of the bobbins B where the weft ends W are wound.

Guide bars 80 (Fig. 6) are supported on brackets 81 at the front and rear of the bobbins B and closely adjacent thereto. These guide bars prevent upward movement of the bobbins during the stripping operation. An additional guide bar 82 (Fig. 1) is mounted at the end of the machine to guide the bobbins around the pulley 16. The stripped bobbins thereafter fall by gravity from the pins 52 into a suitable storage box S.

A finger guard 85 (Figs. 6 and 7) is provided at the front of the belt 14 adjacent the entrance of the bobbins between the guide bars 80. Supports 86 extend upward from the auxiliary frame 30 adjacent the ends of the stripper roll 60 and support a curved cover plate 88 (Fig. 2). A bracket 90 (Fig. 8) is secured to the frame 30 adjacent the detachable bearing bracket 63 for a purpose to be described.

Having described the details of construction of my improved bobbin stripper, the operation thereof is as follows:

35 When the motor M is started, the cross shafts 25 and 20 are continuously rotated, thus causing slow rotation of the stripper roll 60 and slower travel of the conveyor belt 14.

Assuming that the valve 71 is open and that a 40 suitable air pressure is supplied, jets of air will be ejected from the perforations 76 in the tubes 74 and 75 as indicated in Fig. 7. The operator places bobbins B on the pins 52 at the right-hand end of the machine (as viewed in Fig. 1) 45 and the bobbins thereafter travel slowly to the left between the perforated tubes 74 and 75 and below the stripper roll 60.

The jets of air quickly loosen the ends of weft 50 wound on the bobbins and carry the same upward until the ends engage the rough cloth covering of the roll 60 and become attached thereto. Such engagement of the weft with the stripper roll is facilitated by the curved cover 88 (Fig. 2) which tends to deflect the end of the weft 55 against the roll as the weft end is blown upward.

As soon as a weft end is attached to the stripper roll, the rotation of the roll unwinds the remaining weft from the bobbin B, while the 60 guide bars 80 prevent upward displacement of the bobbin if the weft should catch or pull when unwinding.

The rates of travel are so proportioned that any ordinary length of weft end will be completely removed from its bobbin before the bobbin reaches the left-hand end of the conveyor, whereupon it is deposited in the storage box S.

The weft ends are thus removed from the bobbins without contact of any mechanical structure with the barrels of the bobbins and without 70 the possibility of injury thereof, which is a very important consideration when weaving silk or other very fine and delicate weft.

When it is desired to remove the accumulated weft from the stripper roll, the clamping screw 75 65 is taken out, the bearing bracket 63 removed,

and the roll shaft 61 is swung around to the dotted line position shown in Fig. 8, in which position the roll 60 is supported while the cloth casing 66 is pulled off of the small end of the roll. The accumulated weft may then be easily removed from the collapsed cloth cover, after which the cover may be replaced and the stripping operation resumed.

Having thus described my invention and the advantages thereof, I do not wish to be limited to the details herein disclosed, otherwise than as set forth in the claims, but what I claim is:—

1. A bobbin stripper comprising a stripper roll, means to rotate said roll, a bobbin conveyor, means to drive said conveyor to move said bobbins substantially axially of said roll but spaced therefrom, means to loosen the weft ends on bobbins on said conveyor and to cause said loosened weft ends to engage said stripper roll, and means to prevent displacement of said bobbins on said conveyor during subsequent unwinding of the wefts therefrom by said stripper roll. 20

2. A bobbin stripper comprising an elongated stripper roll, means to rotate said roll, a bobbin conveyor movable substantially parallel to the axis of said roll but spaced therefrom, means to drive said conveyor, means to support bobbins in spaced relation on said conveyor with the tips thereof directed toward said roll, and means to blow a weft end loose from each bobbin and into engagement with said stripper roll. 25

3. A bobbin stripper comprising an elongated stripper roll, means to rotate said roll, a bobbin conveyor movable substantially parallel to the axis of said roll but substantially spaced therefrom, means to support bobbins in spaced relation on said conveyor with the tips of said bobbins directed toward said roll, and perforated pneumatic tubes extending at each side of the operative run of said conveyor and below the weft ends wound on said bobbins, whereby said weft ends will be loosened and brought into engagement with said roll. 35

4. A bobbin stripper comprising an elongated stripper roll, means to rotate said roll, a bobbin conveyor movable substantially parallel to the axis of said roll but substantially spaced therefrom, means to support bobbins in spaced relation on said conveyor with the tips of said bobbins directed toward said roll, and perforated pneumatic tubes extending at each side of the operative run of said conveyor and below the weft ends wound on said bobbins, the perforations of said tubes being at the upper inner portions of said tubes, whereby jets of air are directed against the weft ends on said bobbins and toward the tips of said bobbins. 45

5. A bobbin stripper comprising a stripper roll, means to rotate said roll, spaced guide bars extending substantially parallel to the axis of said roll, means to move bobbins successively lengthwise of said roll and between said guide bars, said bobbins being retained on said moving means by said guide bars, and pneumatic means to transfer loosened weft ends from said bobbins to said stripper roll as said bobbins are moved. 55

6. A bobbin stripper comprising a stripper roll, means to rotate said roll, spaced guide bars extending substantially parallel to the axis of said roll, means to move bobbins successively lengthwise of said roll and between said guide bars, pneumatic means to transfer loosened weft ends from said bobbins to said stripper roll, and 70

guide means above said roll effective to deflect a loosened weft end against said roll.

7. A bobbin stripper comprising a stripper roll, means to rotate said roll, a bobbin conveyor, means to drive said conveyor to move a succession of bobbins along a path substantially parallel to the axis of said roll and below said roll, pneumatic means to loosen the weft ends on bobbins on said conveyor and to cause said loosened weft ends to engage said stripper roll, and a guide plate above said roll and effective to direct said loosened weft ends toward said stripper roll.

8. A bobbin stripper comprising a stripper roll, means to rotate said roll, a bobbin conveyor, means to drive said conveyor to move said bobbin substantially axially of said stripper roll but spaced therefrom, and pneumatic means effec-

tive to loosen the weft ends on the bobbins on said conveyor as said bobbins pass said pneumatic means and to cause said loosened weft ends to engage said stripper roll and to be entirely removed from said bobbins by said roll. 5

9. A bobbin stripper comprising a stripper roll, means to rotate said roll, a bobbin conveyor, means to drive said conveyor to move said bobbins substantially axially of said stripper roll but spaced therefrom, and pneumatic 10 means to direct an air blast against the bobbins on said conveyor as said bobbins pass said pneumatic means, whereby the weft ends are loosened from said bobbins and blown toward and caused to engage said stripper roll and to be thereafter 15 entirely removed from said bobbins by said roll.

WILLIAM LONZO.
